UNITED STATES PATENT OFFICE

2,461,128

ROLLER SKATE

George A. Reich, Cleveland, Ohio

Application January 12, 1948, Serial No. 1,691

2 Claims. (Cl. 280—11.28)

1

The invention relates to an improved hanger or truck adjustment for a roller skate.

Another object of the invention is to provide a removably mounted seat in the platform of the truck or hanger made of metal harder than that constituting the hanger so that the bearing surface therein for the bolt head, may be given a very smooth and hard wearing surface, while at the same time the seat is not rendered unduly brittle.

Another important object of the invention is to provide means to position and maintain the inclination of the hanger or truck longitudinally on the bolt head.

I attain these objects by the mechanism illustrated in the accompanying drawing in which:

Figure 1 is a view in side elevation partly in section of a roller skate showing my improvement incorporated therein.

Figure 2 is a plan view thereof.

Figure 3 is a fragmentary view in end elevation.

Similar numerals refer to similar parts throughout the several views.

Referring to the drawing, the shoe supporting plate 1 comprises a body consisting of a metallic plate having integrally formed therewith and on the underside thereof, at or adjacent its ends, longitudinally extending medially situated bosses 2, 2, connected at their inner extremities by means of spaced ribs or stiffeners 3, 3.

As the mechanism at the respective ends, differ in no essential point, a description of one it is thought will suffice for both.

In each boss there is provided a longitudinally extending smooth cylindrical bore 4, centrally located in the longitudinal axis of the shoe plate. The bore extends inwardly to provide an exceptionally long bearing for the cylindrical plug 5 that is held against turning movement within the said bore by means of the reduced end portion 6 of the plug that engages in the slot 7 that extends downwardly from the top surface of the shoe plate perpendicular to the longitudinal axis thereof. This slot stops short of penetrating the thickness of the boss. The slot interrupts the continuity of the thread where it enters the vertical threaded bore 8 in the boss, adapted to receive the threaded portion of the bolt 9. The reduced end portion of the cylindrical plug is provided with an inclined plane 10 adapted to engage and cooperate with the truncated conical end portion 11 of the threaded bolt.

In the cylindrical plug, in the end remote from its reduced end portion there is provided a socket 12 for engaging the ball-shaped head 13 of

2

the member 14 extending from the truck platform 15. The ball-shaped head is held in the socket by means of the integrally formed projecting portions 16 and 17 diametrically opposite and positioned perpendicular to the longitudinal axis of the cylindrical plug. The projecting portions are bent to conform to the surface of the ball-shaped head and are adapted to hold the ball-shaped head captive in the socket while at the same time allowing the ball-shaped head to pivot in the socket.

In the platform 15 there is provided a removably mounted seat or bearing 18 machined to be pressed into the bore 19 adapted to receive it. The seat is provided with an annular shoulder 20 to prevent the seat being pressed beyond its predetermined location in the platform. The seat may be made of special high grade alloy steel and this unique improvement enables the seat to retain its accuracy of shape over a long period, and reduces wear of the seat to a minimum.

The bolt 9 is scientifically hardened throughout, the head portion 21 thereof constitutes a portion of a sphere, the center of which is identical with that of the seat. This obviates the risk of incorrect positioning of the truck when it is tilted on the ball-shaped head in making adjustments of the truck relative thereto.

The truck is provided with an upstanding flange 22 adapted to prevent spreading of the lower portion of the resilient truncated conical cushioning member 23 in making and retaining adjustments.

On the top surface of the cushioning member there is provided a metallic washer 24 on which the lock nut 25 bears. The lock nut is provided to lock the bolt in position after the adjustment has been made. The head of the bolt is provided with a slot 26 to take a screw driver or the like in making the adjustment.

The axle 27 is non-rotatably mounted in the truck structure, and the rollers 28 are removably mounted thereon.

The operation of the device is as follows:

When it is necessary to take up the play of the seat on the bolt head, the bolt is loosened by releasing the lock nut thereon. The bolt is then turned in the proper direction. If clockwise, as the bolt is turned up in the threaded bore in the boss, the truncated conical end of the bolt, which is in engagement with the inclined plane on the reduced end portion of the cylindrical plug mounted slidably in the longitudinal bore in the boss is forced outwardly, carrying with it the ball-shaped head held captive in the end of the

cylindrical plug. The member with the ball-shaped head is connected to the platform of the truck. The resilient member mounted on the platform of the truck resists the adjustment and accommodates itself to its adjusted position thereon. The adjustment of the cylindrical plug causes the platform to tilt, and the resilient conical member mounted thereon holds the cylindrical plug in engagement with the conical end of the bolt, thus maintaining the adjustment. It is obvious that the adjustment may be vice versa.

It will accordingly be seen that I have provided a construction which satisfies the objects of the invention, and while I have shown the invention in a certain physical embodiment, it is to be understood that modifications of structure may be made by those skilled in the art without departing from the invention as expressed in the claims which follow.

What is claimed is:

1. A roller skate comprising, in combination, a shoe supporting member having formed therein longitudinally extending vertical slots of a predetermined depth, medially positioned longitudinally extending bosses integrally formed with and on the underside thereof, spaced ribs connecting the inner extremities of the bosses, each of the aforementioned bosses having therein a longitudinally extending smooth bore, the inner end of which leads into the beforementioned slots, the slots leading into threaded vertical bores in the bosses adapted to receive a threaded bolt having a truncated conical end portion, and a head portion with a spherical surface, the head portion being provided with a tool receiving recess therein, a cylindrical plug having a reduced end portion provided with an inclined plane extending into the slot and also into the threaded bore and also having remote from the reduced end portion a socket therein, the plug being non-rotatably but slidably mounted in the smooth bore, vertically positioned projecting members extending from the socket, a truck having an angularly disposed portion extending upward from the truck and having a portion extending therefrom toward the socket in the cylindrical plug and terminating in a ball-shaped end adapted to engage in the socket to provide a pivotal connection therewith and held in the socket by bending the projecting members to conform to the surface of the ball-shaped end, a platform having a ball seat therein, the threaded bolt extending upward through the ball seat, the spherical surface of the bolt cooperating with the seat, a resilient cushion of truncated conical configuration mounted on the bolt and on the platform, a washer mounted on the cushion, a lock nut mounted on the bolt between the washer and the boss, the truncated conical end of the bolt adapted to cooperate with the plane inclined surface on the reduced end por-

tion of the cylindrical plug, the lock nut adapted to lock the bolt in adjusted position, an axle fast in the truck, and removably mounted rollers on the axle.

5 2. A roller skate comprising, in combination, a shoe supporting member having formed therein longitudinally extending vertical slots of a predetermined depth, medially positioned longitudinally extending bosses integrally formed with and on the underside thereof spaced ribs connecting the inner extremities of the bosses, each of the aforementioned bosses having therein a longitudinally extending smooth bore, the inner end of which leads into the beforementioned slots, the slots leading into threaded vertical bores in the bosses adapted to receive a threaded bolt having a truncated conical end portion, and a head portion with a spherical surface, the head portion being provided with a tool receiving recess therein, a cylindrical plug having a reduced end portion provided with an inclined plane extending into the slot and also into the threaded bore and also having remote from the reduced end portion a socket therein, the plug being non-rotatably but slidably mounted in the smooth bore, vertically positioned projecting members extending from the socket, a truck having an angularly disposed portion extending upward therefrom and having a portion extending therefrom inwardly toward the socket in the cylindrical plug and terminating in a ball-shaped end adapted to engage in the socket and to provide a pivotal connection therewith, and held in cooperative relation in the socket by bending the projecting members to conform to the surface of the ball-shaped end, a platform, a removably mounted ball seat therein, the threaded bolt extending upward through the ball seat, the spherical surface of the bolt cooperating with the ball seat, a flexible compressible cushioning member of truncated conical configuration mounted on the platform and the bolt extending therethrough, a washer mounted on the aforesaid cushioning member, a lock nut on the bolt and positioned between the washer and the boss, the truncated conical end of the bolt adapted to cooperate with the inclined plane surface on the reduced end portion of the cylindrical plug, the lock nut adapted to lock the bolt in adjusted position, an axle fast in the truck, and removably mounted rollers on the axle.
